UNITED STATES PATENT OFFICE.

ERNEST DICKEY AND RALPH L. LEE, OF DAYTON, OHIO, ASSIGNEES TO DELCO-LIGHT COMPANY, OF DAYTON, OHIO, A CORPORATION OF DELAWARE.

DOMESTIC APPLIANCE.

Application filed October 3, 1922. Serial No. 592,140.

To all whom it may concern:

Be it known that we, ERNEST DICKEY and RALPH L. LEE, citizens of the United States of America, residing at Dayton, county of 5 Montgomery, and State of Ohio, have invented certain new and useful Improvements in Domestic Appliances, of which the following is a full, clear, and exact description.

10 This invention relates to improvements in portable power units and more particularly to the type of apparatus described in the patent to Ernest Dickey No. 1,383,391, patented July 5, 1921.

15 In said patent there is disclosed a portable power device or power stand which includes a tripod support for an electric motor having a driving pulley to which a driven pulley of a machine may be belted. Generally, 20 this type of power stand rests upon the floor beside the machine to be operated, and there is a spacing device provided between the power stand and the machine for bracing the power stand away from the machine 25 in order to keep the belt taut.

In the present invention it is one of the objects to provide means whereby the support for the electric motor may be pivotally mounted, said support being suspended in 30 mid air, that is, without the weight of the support and motor being transmitted directly to the floor through legs attached to the support. The motor and support are pivotally mounted so as to swing away from 35 the driven pulley of the machine whereby the belt connecting the motor driving pulley with the machine pulley will be held taut by the weight of the motor and support.

In carrying out this aim of the invention, 40 it is a further object to provide suspending means for the motor support which may be attached to the frame of the machine driven by the motor, said suspending means being adjustable in order to bring the motor 45 pulley into alignment with the machine pulley.

A further object is to provide a suspending means for the motor support which is adjustable so that it may be adapted for 50 attachment to the frames of various machines which can be driven by the motor, and to provide such adjustments as will be necessary to bring the motor pulley into the desired elevation with respect to the

machine pulley as well as to bring these two 55 pulleys into alignment.

A further object of the invention is to provide stop means for limiting the fall of the motor and support in case the belt should break. Preferably the motor support is provided with legs by means of 60 which the motor may be supported in position elevated from the floor when the device is not in use. One of these legs may serve as a stop to limit the movement of 65 the motor support in case of the belt breaking.

Other and further objects and advantages of the present invention will be apparent from the following description of a 70 preferred embodiment thereof, reference being made to the accompanying drawings.

In the drawings, Fig. 1 is a side view of the portable device embodying the present invention, and attached to a machine 75 to be driven by the motor;

Fig. 2 is a plan view thereof, a machine frame being shown in section taken on the line 2-2 of Fig. 1;

Fig. 3 is a fragmentary plan view partly 80 in section showing the connection between certain bracing members of the device and the motor support; and

Fig. 4 is a perspective view of certain members shown in Fig. 3, the motor support 85 and the clamping wing nut being shown in detached relation.

Referring to the drawings, a motor 20 having a stepped driving pulley 21 and a handle 22 is attached by bolts 23 to a support 24 provided with legs 25 by means of 90 which the motor may be supported in elevated position when the power device is not in use.

The support 24 is provided with ears 26 95 apertured at 27 and 28 for receiving respectively a rod 29 and a sleeve 30 which is slidable upon the rod 29. The sleeve 30 is provided with a semi-cylindrical extension 31 which cooperates with a similarly formed extension 32 of the sleeve 33 100 which is also slidable upon the rod 29. When the sleeves 30 and 33 are caused to move together as will be explained later these portions 31 and 32 will clamp around 105 a pin 34 which is carried by a clevis 35 which is screw threaded upon a tube 36. Tube 36 receives a rod 37 having a hook

38 for cooperating with an eye 39 which is provided on a clamp 40 which is constructed for ready attachment to a projection from a machine frame such as the ledge 41 extending out from the pedestal 42 of a machine 43, such as a cream separator, for example.

The rod 29 carries two other clamping sleeves 33 which cooperate to provide a 10 clamping bearing for another pin 34 which has connections with the machine frame identical with those between the machine and the first described pin 34. One of these sleeves is pinned at 45 to the rod 29. Each 15 of the pins 34 is attached to a clevis 35 by means of pins 46. The rod 29 is threaded at 47 to receive a wing nut 48 and to receive a locking nut 49.

Between spaced clamping sleeves 33 is a 20 sleeve 50 having an extension 51 for receiving a tube 52 which is telescopically engaged with a rod 53. The rod 53 is secured in adjusted position with respect to the tube 52 by means of a clamping screw 54, and each of the rods 37 may be clamped in adjusted relation to each of the tubes 36 by means of a clamping screw 55.

To mount the power device in driving relation to a machine, the user will usually 30 grasp the handle 22 and lift the motor 20 into the desired elevation with respect to the machine pulley 60, and will connect the pulleys 21 and 60 by means of a belt 61. The strut members 52 and 53 are then clamped 35 in adjusted position so that the support 24 will be suspended at the desired elevation, the member 53 resting upon the floor or upon the base of the machine frame if convenient. The bracing rods 37 are withdrawn 40 from the tubes 36 so that the hooks 38 may engage the eyes 39 of the clamps 40 which have been attached to the machine frame in a convenient position. The strut members 52, 53 are so located as to bring the motor pulley 21 substantially into alignment with the machine pulley 60 and the brace members 36, 37 are so clamped in adjusted position by the clamping screws 55 that the axes 45 of the pulleys 60 and 21 will be parallel. It is apparent that since the clamps 40 and the pins 34 are spaced from each other that a trapezoid may be considered to be bounded by the brace members 36, 37, a line joining the pins 34 and a line joining the clamps 50 40. So long as the pins 34 are free to turn with respect to the clamping sleeves 30, 33, and 33, 33, respectively, the angular adjustment of the bracing members 36, 37 with respect to the rod 29 may be varied. In 55 case the machine frame is not constructed to facilitate attachment of the clamps 40 in a manner that will bring a line joining the eyes 39 into parallelism with the axis of pulley 60, then the bracing members 36, 37 60 may be adjusted as to length and as to their

angular relation to the rod 29 in order to locate the axis of the motor pulley 21 parallel to the axis of machine pulley 60, while these pulleys are brought into vertical alignment.

After the foregoing adjustments have been made the clamping nut 48 is screwed in along the rod 29, thereby causing the members 30, 33, and 50 all to be clamped together, and the lock nut 49 is tightened down to secure the clamping nut 48 in position. The bracing members can not now swing with respect to the motor support 24 since the pins 34 attached to these members are prevented from turning with respect to the clamping sleeves carried by the rod 29. However, the motor support 24 is still free to swing around the pivot rod 29, therefore it is apparent that the bracing members and strut members and parts attached thereto constitute means for providing a pivotal suspension for the motor support whereby the motor may be suspended above a floor and its weight may be utilized in maintaining taut the belt connecting the motor and machine pulleys. As explained before the strut member and the bracing members are adjustable so that the pivotal supporting means can be secured to a variety of machine frames with the motor and support in correct driving relation to the machine. When this supporting means has been attached, the machine together with the supporting means constitutes a rigid structure from which the motor and its support is suspended.

In case the belt should break the motor support 24 will swing downwardly, but one of the legs 25 will strike the floor and will act as a stop member limiting the movement 105 of the motor support. While it is not necessary to provide the motor support with legs it is preferable to do so in order that the motor may be supported in elevated position and be readily accessible when not in use, and in order to prevent the motor from being set down in refuse, dirt, or mud which accumulates on the floor or ground of the places where the present invention is used.

It will of course be understood that when provided with the supporting legs 25, the motor is susceptible of use in the same manner as shown and described in the aforesaid Dickey patent, that is, with the legs 25 resting on the floor and supporting the weight of the motor, one or both of the bracing members 36, 37 being connected to the work machine to hold the power device in proper spaced relation to the work machine.

While the form of mechanism herein shown and described constitutes a preferred embodiment of one form of the invention, it is to be understood that other forms might be adopted and various changes and alterations made in the shape, size, and pro-

portion of the elements therein without departing from the spirit and scope of the invention.

What is claimed is as follows:

5. 1. In a portable power device, the combination with a motor having a driving pulley for belted connection with the pulley of a work machine; of strut and bracing members connected with the motor, said strut and bracing members engaging the frame of the work machine, said members and said frame constituting a rigid support adapted to support the motor.
10. 2. In a portable power device, the combination with a motor having a driving pulley for belted connection with the pulley of a work machine; of strut and bracing members pivotally connected with the motor, each of said members being adjustable as to length, one of said members engaging a stationary part and another of said members engaging the frame of the work machine, said members and said frame constituting a rigid support for supporting the motor, the adjustment of said members providing a universal adjustment for the motor for adjusting its position and the alignment of the pulleys.
15. 3. In a portable power device, the combination with a motor having a driving pulley for belted connection with the pulley of a work machine; of a strut member pivotally connected with the motor and engaging a stationary part; bracing members each having one end engaging the frame of the work machine and having pivotal connections with the motor, said connections being spaced whereby the angular relation between the bracing and strut members and the motor may be varied; and means for clamping said bracing members in fixed angular relation with respect to the motor and the strut member.
20. 4. In a portable power device, the combination with a motor having a driving pulley for belted connection with the pulley of a work machine; of a strut member pivotally connected with the motor and engaging a stationary part, said strut member being adjustable as to length; bracing members adjustable in length and each having one end engaging the frame of the work machine and each having at the other end a universal joint connection with the motor, said connections being spaced whereby the angular relation between the bracing members and the motor may be varied.
25. 5. In a portable power device, the combination with a motor having a driving pulley for belted connection with the pulley of a work machine; of means for supporting the motor pivotally above a stationary part, said means including bracing members each having one end detachably secured to the frame of the work machine and each having at the other end a universal joint connection with the motor, said connections being spaced whereby the angular relation between the bracing members and the motor may be varied; and means for clamping the bracing members in adjusted position.
30. 6. In a portable power device, the combination with a motor having a driving pulley for belted connection with the pulley of a work machine; of means for supporting the motor pivotally above a stationary part, said means including bracing members adjustable in length and each having one end detachably secured to the frame of the work machine and each having at the other end a universal joint connection with the motor, said connections being spaced whereby the angular relation between the bracing members and the motor may be varied; and said connections permitting adjustments in the length of the bracing members; and means for clamping the bracing members in adjusted position.
35. 7. In a portable power device, the combination with a motor having a driving pulley for belted connection with the pulley of a work machine; of means for supporting the motor pivotally above a stationary part, said means including bracing members adjustable in length and each having one end detachably secured to the frame of the work machine and each having at the other end a universal joint connection with the motor, said connections being spaced whereby the angular relation between the bracing members and the motor may be varied; and said connections permitting adjustments in the length of the bracing members; and means for clamping the bracing members in adjusted position.
40. 8. In a portable power device, the combination with a motor having a driving pulley for belted connection with the pulley of a work machine; of means for supporting the motor pivotally above a stationary part, said means including bracing members having universal joint connections with the frame of the work machine and with the motor, respectively, said joint connections being spaced from each other whereby the angular relation of the bracing members to the motor may be varied and means for clamping said bracing members in adjusted position.
45. 9. In a portable power device, the combination with a motor having a driving pulley for belted connection with the pulley of a work machine; of means for supporting the motor pivotally above a stationary part, said means including bracing members each having a universal joint connection with the frame of the work machine, each joint connection being adjustably secured to the work machine whereby the spacing between said joint connections may be varied, and

- said bracing members each having a universal joint connection with the motor, said connections being spaced closer than the connections with the machine frame whereby upon swinging said bracing members side-wise the axis of the motor pulley may be brought into parallelism with the axis of the machine pulley; and means for securing the bracing members in adjusted position.
10. In a portable power device, the combination with a motor having a driving pulley for belted connection with the pulley of a work machine; of a supporting base for the motor and legs therefor; and means

adapted to be detachably secured to the frame of the work machine for providing pivotal suspension for said supporting base whereby the weight of the motor and the base will keep taut said belted connection, but in case the belt breaks the supporting base will be supported by one of the legs.

In testimony whereof we hereto affix our signatures.

ERNEST DICKEY.
